UNITED STATES PATENT OFFICE

RICHARD ZINKERNAGEL, OF NEW YORK, N. Y., ASSIGNOR TO INTERNATIONAL COMBUSTION ENGINEERING CORPORATION, OF NEW YORK, N. Y., A CORPORATION OF DELAWARE

TRAVELING GRATE STOKER

Application filed September 17, 1927. Serial No. 220,203.

My invention relates to traveling grate stokers and has special reference to means for preventing excess blowing of air and excess leakage of fuel at the sides of the grate of such 5 stokers.

An object of the invention is to provide novel and improved sealing means of this character.

Another object of my invention is to provide 10 means of the character indicated that are adjustable from the exterior of the furnace to compensate for contraction and expansion of the upper run of the grate.

The several features of the invention, 15 whereby the above mentioned and other objects may be attained, will be clearly understood from the following description and accompanying drawings, in which,

Figure 1 is a transverse sectional view of 20 a traveling grate stoker embodying the features of the invention in their preferred form;

Fig. 2 is a sectional plan view, taken on the line 2—2 of Fig. 1;

Fig. 3 is a detail view in perspective of a 25 portion of a component part of my improved sealing means; and

Fig. 4 is a longitudinal sectional view, partly diagrammatical, of a portion of the improved stoker.

The stoker illustrated in the drawings is provided with the usual chain grate 2, and combustion chamber 4 having longitudinal side walls 6 and front and rear walls 8 and 35 10, respectively. The stoker is further provided with a series of side sealing members 12 that are arranged end to end and rest upon a shelf 14 formed on each of the longitudinal side frames 16 of the stoker. Each sealing member 12 has a flat portion 18 at the upper 40 part of its inner side that is adapted to engage outwardly projecting ribs 20 on the outer links of the chain. A steel strip or bar 22 has its inner portion resting upon the outer 45 portion of the top surface of the sealing members of each series and has its outer portion received in a longitudinally extending groove 24 in the associated longitudinal side frame 16. A ledge plate 26 is mounted in each of 50 the longitudinal side walls 6 and extends over

the top of the associated side frame 16 and the steel strip or bar 22, and has a depending rib portion 28 that is arranged adjacent the inner side of the bar 22 with its bottom side arranged in close proximity to the inner portion of the top surfaces of the sealing members 12.

Except as hereinafter described, the parts above referred to may be, and preferably are, substantially the same as the corresponding 60 parts of the traveling grate stoker described and claimed in my co-pending application Serial No. 220,202, filed September 17, 1927.

In accordance with my present invention, means is provided which is controllable by 65 the operator from the front of the furnace for adjusting the side sealing members toward the sides of the grate, and for permitting them to be moved in a direction away from the grate, to compensate for contraction 70 and expansion of the grate. As shown, the steel strip or bar 22 has a plurality of plates 30 secured to its under side. Each of these plates 30 is provided with an inclined or cam surface 32 which is adapted to engage the 75 outer sides of abutting end portions of adjacent sealing members, the ends of the sealing members having outwardly projecting ribs 34 and the outer surfaces of the ribs being inclined to conform with the associated cam 80 surface 32.

The forward end of each bar 22 extends beyond the front of the furnace and has an upturned end portion 36 which is provided with an aperture 38. A bolt 40 extends 85 through this aperture and its inner end is secure in the front wall of the stoker. Nuts 41 are arranged on the bolt at opposite sides of the portion 36 so that by adjusting the 90 nuts each bar 22 may be moved rearward 90 and forward and held in adjusted position.

With this construction it will be apparent that upon adjusting each bar 22 forward the cam plates 30 will gradually force all of the 95 sealing members of the associated series toward the side of the upper run of the grate, and that upon adjusting each bar 22 rearward the sealing members are permitted to work away from the upper run of the chain 100

when they have been forced into too close engagement therewith.

It will be apparent that the sealing members on both sides of the upper run of the grate may be easily adjusted by the operator from a convenient position at the front of the furnace.

As will be evident to those skilled in the art, my invention permits various modifications without departing from the spirit thereof or the scope of the appended claims.

What I claim is:

1. A traveling grate stoker having, in combination, side sealing members arranged adjacent the longitudinal sides of the upper run of the grate, and means under the control of the operator from the front of the stoker for moving said sealing members toward the sides of the grate.

2. A traveling grate stoker having, in combination, side sealing members arranged end to end adjacent at least one of the sides of the upper run of the grate, and devices under the control of the operator from the outside of the stoker for moving said members toward said side.

3. A traveling grate stoker having, in combination, side sealing members arranged end to end adjacent at least one of the sides of the upper run of the grate, a bar mounted for movement longitudinally of the grate, and means carried by said bar for moving said sealing members toward said side of the grate upon movement of the bar longitudinally in one direction.

4. A traveling grate stoker having, in combination, side sealing members arranged end to end adjacent at least one of the sides of the upper run of the grate, a bar mounted for movement longitudinally of the grate, and members having cam surfaces for engagement with the outer sides of said sealing members for moving said sealing members toward said side upon movement of said bar in one direction.

5. A traveling grate stoker having, in combination, side sealing members arranged end to end adjacent at least one of the sides of the upper run of the grate, a bar mounted for movement longitudinally of the grate, and members having cam surfaces for engagement with the outer sides of said sealing members for moving said sealing members toward said side upon movement of said bar in one direction, means for moving said bar in said direction and permitting said bar to be moved in the opposite direction to permit said sealing members to be moved in a direction away from said grate.

6. A traveling grate stoker having, in combination, side sealing members arranged adjacent at least one of the sides of the upper run of the grate, a shelf on which said side sealing members are mounted, a bar arranged longitudinally of said side sealing members

and having its inner portion resting upon the outer portion of the top side of said side sealing members and movable longitudinally of the grate, a ledge plate mounted in the furnace wall and having its inner portion extending over and in close proximity to the inner portion of the top sides of said sealing members and adjacent the inner side of said bar, and means carried by said bar acting upon movement of the bar in one direction to move said side sealing members in a direction toward said side of the grate.

7. A traveling grate stoker having, in combination, side sealing members arranged adjacent at least one of the sides of the upper run of the grate, a shelf on which said side sealing members are mounted, a bar arranged longitudinally of said side sealing members with its inner portion resting upon the outer portion of the topside of said side sealing members, means for moving said side sealing members toward said side of the grate upon movement of said bar in one direction, comprising cam plates secured to the under side of said bar and adapted to operatively engage the outer sides of said side sealing members.

In testimony whereof, I have signed my name to this specification this 15th day of September, 1927.

RICHARD ZINKERNAGEL.
